United States Patent Office.

WILBER S. WANDELL, OF BATTLE CREEK, MICHIGAN.

Letters Patent No. 75,607, dated March 17, 1868.

IMPROVEMENT IN GATES.

The Schedule referred to in these Letters Patent and making part of the same.

TO ALL WHOM IT MAY CONCERN:

Be it known that I, WILBER S. WANDELL, of Battle Creek, in the county of Calhoun, and State of Michigan, have invented a new and improved Gate; and I do hereby declare that the following is a full, clear, and exact description thereof, which will enable others skilled in the art to make and use the same, reference being had to the accompanying drawings, forming part of this specification.

The drawing is an elevation of my improved gate with certain removed sections, exhibiting its mechanism.

This invention relates to self-opening gates; and consists in so hanging and weighting the same that it will swing upward when the gate is turned horizontal, or its latch-pin is liberated.

In the drawing, A is the gate, B a portion of the fence, C the post supporting the gate, and D the other post, to which the gate is latched when closed.

The upper and lower frames, *a*, of the gate, extend beyond the upright frame-piece *d*, and are made with holes or bearings, for the reception of the round tenons, *e*, formed on each end of a swivel-post, *f*. This swivel-post is hung on the fence-post *C* by means of a round pin, *n*, projecting horizontally from the latter, and which acts as a swivel-pin. On this pin the gate is made to turn down horizontally, in the first act of being opened. Weights, *E*, are fastened to the projecting ends of the frame-pieces *a*. In practice, these weights would be strong boxes, filled with sand or stone, and are to be made sufficiently heavy to more than balance the gate, so that when the opposite end of the same is liberated, the gate will swing upward, nearly or quite perpendicularly, thus leaving a vehicle or person free to pass through. The weights are equal, and equidistant from the swivel-pin *n*, so that the gate is balanced, as to its horizontal rotation, and can be turned down in the first act of being opened, with but a slight application of power.

A spring-bar, *h*, provided with pins, *m* and *m'*, is bolted or otherwise secured, at one end, to the post *D*. The pins pass through holes in the said post, and project beyond the same sufficiently to enter their points in the upright, *g*, of the gate-frame, as shown. In opening this gate, the spring-bar is seized at *h*, and pushed outward from its post till the pin *m'* has withdrawn from the upright, *g*. The gate is then turned down horizontally, and the lower frame *a* leaves the slot *r*, made in the post *C*, for the purpose of allowing the gate to hang vertically, as well as to steady the same. After the gate has been turned down in the manner described, the bar *h* is pushed further out, till the pin *m* is withdrawn from the upright, *g*, when the weights *E* will swing the gate upward and vertical, leaving a clear passage through. In shutting the gate, it is only required to bring down the gate and catch the pin *m*, then turn the gate vertical, and catch the secured pin *m'*. This pin *m'* may be dispensed with, if desired, and only the pin *m* used, for the slot *r* in the post *C* will act as a catch to keep the gate closed until the frame-piece *a* leaves it, when the gate is turned horizontally.

Thus, this improved gate dispenses with the ordinary metallic hinges or pintles for hanging the same, and from the slight preponderation of the weights, will not sag or droop down, as is frequently the case with other gates. It cannot be obstructed in its operation of opening, by drifted snow, as those gates that swing open laterally.

I am aware that a gate has been patented by C. Van Hoesen, (April 20, 1852,) which is swung upward by a weight, in a manner similar to mine; but his gate does not turn down horizontally, and thus a portion of the passage is obstructed by the lower corner of the gate, which is likely to catch against any bulky vehicle passing through it, as a load of hay, and twist or strain the gate, or drag off part of the load.

I do not claim broadly, a gate swung upward by a weight, for those have been made, but

What I claim as new, and desire to secure by Letters Patent, is—

The pins *m* *m'*, upon the spring *h*, in combination with the weighted gate *A* and pin *n*, whereby, as the pin *m'* is withdrawn by the spring *h*, the gate is permitted to swing into a horizontal position upon the pins *m* *n*, for the passage beneath it of hogs or sheep, as herein shown and described.

The above specification of my invention signed by me, this 2d day of September, 1867.

WILBER S. WANDELL,
